UNITED STATES PATENT OFFICE

2,051,191

CARPET AND RUG FASTENER

Ernest Watson, Wauwatosa, Wis.

Application May 9, 1932, Serial No. 610,153

2 Claims. (Cl. 16—16)

My invention relates to means by the use of which carpets and rugs may be held in fixed position in relation to a floor, the whole or a part of the area of which it is desired to cover.

5 Such invention resides in the provision of a metal strip of considerable length, and of comparatively narrow width, folded upon or near its longitudinal center line, so that the folded sides of the strip lie parallel and receive between them 10 the folded over edge or margin of the carpet or rug.

The lower side of the folded metal strip is perforated at points in its length for the reception of nails or screws, by means of which the fastener 15 is secured in the desired position upon the floor. The upper side of the folded strip is provided with projections or teeth which are adapted to enter the back of the folded over edge or margin of the carpet or rug, and firmly hold the carpet or rug 20 against change in its position upon the floor, or distortion of the alignment of its edges.

If the entire floor is to be covered by a carpet, the fasteners will be secured to the floor in close proximity to the base board, all around the room.

25 If a selected area only of the floor is to be covered by a rug, the fasteners will be secured to the floor in correspondence with the dimensions of the rug. After the fasteners have been secured to the floor as described, each edge or margin of the 30 carpet or rug will be folded over the edge of the free side of the metal strip, which free side will then be folded down upon the lower side of the strip, with the folded over edge or margin of the carpet or rug embraced and secured between.

35 In this manner, the carpet or rug will be placed under tension, and the surface of the same will be preserved in an even plane. The fastening strips are entirely concealed, and no nail heads are exposed to view.

40 Having thus outlined the nature and purposes of my invention, I will now describe the specific construction illustrated, and in the appended claims will point out the novelty residing in the invention.

45 In the accompanying drawing:

Figure 1 is a traverse section view of my improved fastener, secured in position upon the floor, and ready for the engagement therewith of the edge or margin of the carpet or rug.

50 Fig. 2 is a perspective view, broken out to save space, of one of the strips embodying my invention.

Fig. 3 indicates in an open view how the first fastening of an edge or margin of a carpet or rug 55 is positioned between the two sides of the fastener,

preparatory to securing the carpet or rug, and before tension has been applied at the opposite edge or margin.

Fig. 4 shows a completion of the operation initiated in Fig. 3.

Fig. 5 is similar to Fig. 4, but showing an underlying carpet lining in position.

Fig. 6 shows a construction designed for the accommodation of carpets having a deep pile.

Fig. 7 shows a special adaptation of the invention, which later will be described.

Fig. 8 shows an embodiment of the invention in a simplified form.

In the drawing, the carpet or rug fastener is shown as embodied in a metal strip A of considerable length, but of narrow width in comparison with its length. The strip is bent as at 10, on or near its longitudinal center line, so as to provide a lower side or portion 11 and an upper side or portion 12. Such bending is merely a preparatory operation, and while I have shown the sides or portions 11 and 12 of the strip as standing at a 90° angle with respect to each other, the angular relation may be as desired, or to stand at any such angle as will enable the functions of the invention, as hereinafter described, to be effected.

The lower side 11 of the strip A is provided at points throughout its length with perforations 13, into which may be passed screws or nails, or other devices, by means of which the strip will 30 be secured in the desired position upon the floor which is to be covered. The upper side 12 of the strip may be partially perforated at points in its length, to provide the teeth or projections 14, extending inwardly of the side 12 of the strip, 35 or into the bight of the completely folded strip. Such teeth or projections 14 should stand normal to the plane of the inner face of the side 12, or extend toward the line 10, on which the strip is bent, so as to hold the fabric from slipping, after 40 such teeth or projections have been engaged in the back of the same.

The longitudinal free edge of the side 12, preferably will be cut so as to provide thereon a series of spaced teeth or projections 15, extending 45 the length of the strip, and functioning as before described with reference to the teeth or projections 14. In some instances, one or the other of the series of teeth or projections 14 or 15, may be omitted in producing the strip, without interfering with its efficiency as a fastening device.

In using my invention, the strips A are secured to the floor in position to define the area which is to be covered by the carpet or rug, the side 55

12 of the strips then standing vertically or at any other desired angle. One loose edge or margin of the carpet or rug 16 is folded over the upstanding edge of the side 12 of the strip, at the 5 left, for instance, and extended into the angle formed by the bend 10. The side 12 is then pressed down or further bent so as to lie parallel with the lower side 11 of the strip. In such action, the teeth or projections 14 and 15 are 10 caused to enter the carpet or rug from the back, and the carpet or rug is prevented from slipping, by both the engagement of the teeth or projections, and by the frictional engagement of the folded-together sides 11 and 12 of the strip A.

15 The opposite edge of the carpet or rug 16, is now turned over the upstanding side 12 of the companion strip A, the one at the right, for instance, the fabric being stretched to take up the slack, and caught upon all of the teeth or projections with which the said side of the strip is 20 provided. Now, by folding the side 12 down upon the lower side 11 as before, the opposite folded over edges or margins of the carpet or rug will be securely engaged by all of the teeth or projections with which the upper sides of the strips A are provided, as well as being clamped between the folded sides of the strips A. In pressing down the side 14 of the second strip, the carpet or rug 16, is stretched and placed under tension, 30 so as to present a smooth face. The underside of the margin of the fabric is engaged throughout the length of the margin, and displacement of the straight edge in the line of the fold in the fabric is prevented.

35 The other opposite edges or margins of the carpet or rug are then operated upon in the same manner, so that the four edges or margins of the carpet or rug will be firmly held in position, and undesired displacement is prevented.

40 Fig. 5 shows a lining 17, for the carpet or rug, the said lining obviating what otherwise would be a raised border, such as is shown in Fig. 4.

Fig. 6 shows a special arrangement to provide accommodation for carpets or rugs having deep pile, and enables the raised border to be eliminated. A shallow channel 18 is cut to define an area equal to that of the carpet or rug, and the strip A, forming the fastener, is placed therein. The folded over edge or margin of the carpet or rug lies in the channel, below the plane of the 45 surface of the floor.

50 Fig. 7 shows an adaptation of the fastener to the cover of a table or desk.

Fig. 8 shows the invention in a simplified form. The narrow metal strip 20 is divided on a longitudinal line into two side margins, 21 and 22. The margin 21 is perforated, as before, for attachment to the floor. The margin 22 is provided with teeth or projections which engage the back of the carpet, as before described, and clamp the edge or margin of the carpet or rug, when the margin 22 is pressed down into a plane parallel to the plane of the side 21.

10 The carpet or rug may easily be removed, if desired, by simply opening up the fastener, and disengage the edges or margins of the fabric from the teeth or projections. Restoration of the fabric will be made in the manner first described. The present invention grips the carpet or rug at points closely spaced in the length of the edge or margin of the fabric, and thus preserves the symmetrical outline of the same. In all forms of the invention, the fastening strip 20 is entirely concealed from view when the carpet or rug is laid, and no nails are exposed.

Having thus described my invention, what I claim and desire to secure by Letters Patent of the United States is:

1. A concealed carpet fastener composed of an elongated metal strip bent longitudinally to constitute a fastener having two parallel sides, the lower side being perforated to permit permanent attachment of the fastener to the floor, and the upper side being provided with teeth or projections over the free edge of which upper side the margin of the fabric is adapted to be folded, and which teeth or projections are adapted to engage the fabric at its under side, and retain the same 35 against displacement of its aligned margin when the upper side of the fastener is pressed down upon the folded margin of the fabric to clamp the same.

2. A concealed carpet fastener composed of an elongated metal strip bent longitudinally to constitute a fastener having two parallel sides, the lower side being perforated to permit permanent attachment of the fastener to the floor, and the upper side being provided with teeth or projections 40 on its free edge adapted to engage a fabric folded over such edge, and other projections to engage the fabric at its under side, and retain the same against displacement of its aligned margin when the upper side of the fastener is pressed down upon the lower side, with the folded margin of the fabric clamped between the said sides. 45

50 ERNEST WATSON.
